UNITED STATES PATENT OFFICE.

PAUL L. MARDIS, OF SWISSVALE, PENNSYLVANIA, ASSIGNOR TO WESTINGHOUSE ELECTRIC & MANUFACTURING COMPANY, A CORPORATION OF PENNSYLVANIA.

CONTROL APPARATUS.

1,414,431.

Specification of Letters Patent.

Patented May 2, 1922.

Application filed March 7, 1919. Serial No. 281,129.

To all whom it may concern:

Be it known that I, PAUL L. MARDIS, a citizen of the United States, and a resident of Swissvale, in the county of Allegheny and State of Pennsylvania, have invented a new and useful Improvement in Control Apparatus, of which the following is a specification.

My invention relates to control apparatus and particularly to controllers of the automotoneer type for preventing a too rapid movement of control drums or the like.

One object of my invention is to provide an apparatus of the character indicated, whereby a simple and reliable check is placed upon movements of a controller handle to prevent injury to the apparatus to be controlled by reason of supplying too heavy a current thereto.

More specifically stated, it is an object of my invention to provide a plate or top cover for a controller having two concentrically-related sets of stops or lugs so shaped as to intermittently effect positive stops of the handle and the associated controller in a plurality of desired positions.

Other minor objects of my invention will become evident from the following detailed description, taken in conjunction with the accompanying drawing, wherein—

Figure 1 is a plan view of a controller handle and a cover member constructed in accordance with my invention.

Fig. 2 is a sectional view, taken along the line II—II of Fig. 1.

Fig. 3 and Fig. 4 are developed views taken along the lines A—B and C—D, respectively, of Fig. 1.

Referring to the drawing, the apparatus shown comprises a plate or top cover member 1 for a controller casing 2 of a familiar type, the controller shaft 3 extending upwardly through the cover member 1 and being provided with a square head 4 to which is fitted my operating handle 5.

The plate or cover member 1 is provided with two sets of concentrically-related stops or lugs, best shown in Fig. 3 and Fig. 4, respectively, the outer set being numbered from 6 to 11, inclusive, and the inner set from 12 to 15, inclusive. Each of the stops has a sloping and a perpendicular face for purposes to be described, the stop 6 having its perpendicular face located along the

line marked "Off", corresponding to one of the off or circuit-opening positions of the controller, while the lugs 7 and 8 have their perpendicular faces respectively in alignment with the positional lines marked "1—For." and "2—For.", reference being had to the first and second forward-operating positions of the controller. The lugs 7 and 8 have their perpendicular faces turned in the opposite direction to that of the stop 6, for a purpose to be hereinafter set forth.

The stops 9, 10 and 11, located on the other side of the intermediate "brake" position of the controller, correspond, respectively, to the lugs 6, 7 and 8 and are located in positions corresponding to Off, First reverse and Second reverse, respectively, reference being made to the operation of the apparatus to be controlled.

Considering the inner circle of stops, those numbered 13 and 15 are exact counterparts, in structure and radial location, of the lugs 8 and 11, respectively, of the outer circle, while the stops 12 and 14 face in similar directions to the lugs 13 and 15, respectively, but are positioned close together to provide a centrally-located notch corresponding to the "brake" position of the controller.

The operating handle 5 comprises a channel or chambered member 16, one end of which is provided with a hole to fit over the square head 4 of the controller shaft, while, near the other end, a grip or handle proper 18 is secured. A pin or button 19 extends upwardly through a longitudinal opening in the grip 18 and is normally maintained in its illustrated upper position by reason of engagement with an inverted U-shaped member 20 which is oscillatable about an intermediate pivotal point 21 and is biased, through the agency of a suitably located helical spring 22, toward the illustrated position, wherein its right-hand arm 23 is in position to engage one of the stops of the inner circle. The left-hand arm 24 of the U-shaped member 20 is located above the outer row of stops or lugs for the purpose of successively engaging them, under operating conditions to be described.

A coil spring 25 has its ends respectively secured to the plate or cover member 1 and to the controller shaft 3 to rotatively bias the shaft and, therefore, the controller

drum toward the intermediate position marked "Brake". For the sake of greater clearness, however, the operating handle 5 is illustrated as occupying the left-hand off position rather than its normal or biased position "Brake". In practice, the controller is also provided with electrical contact members or mechanical means for effecting an emergency application of the vehicle air-brakes when the controller handle returns to its normal position, such, for example, as the structure shown in a copending application of Arthur J. Hall, Serial No. 834,546, filed April 25, 1914, and assigned to the 10 Westinghouse Electric & Manufacturing Company.

Assuming that the controller occupies its normal or biased position "Brake," then the U-shaped member 20 and the actuating pin 20 19 occupy the positions shown in Fig. 2, the right-hand arm 23 being located in the notch between the lugs 12 and 14 of the inner circle. Consequently, no movement of the handle can be effected until the pin 19 is depressed by the hand of the motorman to remove the arm 23 from the notch in question and allow rotative movement of the handle over the cover member 1, as far as the stop or lug 9. The lefthand arm 24 of the U-shaped member 20 rides along the inclined surface of the stop 9, whereby the handle reaches the off position and the pin 19, which has been pushed upwardly by contact of the arm 24 with the stop 9, may again be depressed.

Further movement towards the left is halted by the lug 10 at position marked 1—Rev., since the perpendicular face of the lug 10 is thereupon engaged by the arm 24. 40 To effect movement of the controller handle beyond the lug 10, the pin 19 must be allowed to reassume its illustrated upper position, whereupon the motorman will again press downwardly upon the pin 19 and move the handle towards the left.

Any desired number of intermittent stops of the character just described may be made, thus providing the desired checking action upon the movements of the operator to prevent the controller from supplying an unduly large current to the apparatus being controlled. In the drawing, however, for the sake of simplicity, the position marked 2—Rev. may be considered as the final reverse position and, therefore, the stops 11 and 15, forming parts of the outer and the inner circle of stops, respectively, are provided to prevent movement beyond this final position, regardless of whether the operator maintains the pin 19 in its depressed position or not.

Upon returning the controller towards its off position, the arm 24 of the oscillatable member 20 rides along the inclined surface of the lug 10 and finally strikes the perpendicu-

lar face of the lug 9, corresponding to the off position, whereby movement of the drum is halted in the corresponding circuit-opening position.

It will be appreciated that analogous step-by-step movement of the controller handle is effected through the positions lying to the right of the intermediate "brake" position. In this way, a positive stop of the controller handle, corresponding to each notch in forward or reverse travel, and a positive stop in the off position, during the return movement, is effected. Thus, the operator is prevented from accidentally throwing his controller handle to the braking notch to stop the vehicle and lose time when he merely intended to return the handle to the off position to permit coasting of the vehicle, in readiness for another control operation.

Should the motorman remove his hand from the grip 18 and the pin 19 in any except the intermediate "brake position" of the controller, then the coil spring 25 immediately returns the handle to the "brake" position to effect the above-mentioned emergency application of the air-brakes or any other equivalent or desirable control arrangement. Under these conditions, also, the electrical accelerating circuit is, of course, broken.

I do not wish to be restricted to the specific structural details or arrangement of parts herein set forth, as various modifications may be made therein without departing from the spirit and scope of my invention. I desire, therefore, that only such limitations shall be imposed thereupon as are indicated in the appended claims.

I claim as my invention:

1. The combination with a movable handle embodying a rocking member, of independent sets of stationary means for engaging opposite ends of said member to effect positive stops of said member in a series of positions.

2. The combination with a rotatable device embodying a rocking member, of concentrically related sets of stationary means for engaging opposite ends of said member to effect positive stops of said member in a plurality of radial positions.

3. The combination with a plural-part member, of independent sets of stationary means for selectively engaging opposite ends of one of the member parts during rocking movement of said member.

4. The combination with a rotatable device embodying a rocking member, of a plurality of concentrically located sets of stationary stops for respectively engaging different ends of said member to intermittently interrupt the rotative movement of said device.

5. The combination with a rotatable handle having one part that rocks with respect to another, of an outer and an inner circle

of stops, and means forming a portion of said handle for selectively effecting engagement of opposite ends of said rocking part with the one or the other circle of stops.

5 6. The combination with a rotatable handle having a rocking member biased to a certain position, of an outer and an inner circle of stops, and means forming a portion of said handle for overcoming or yielding to the 10 biasing action to cause said member to engage the one or the other circle of stops during its rocking movements.

7. The combination with a plate having a plurality of sets of stops, of a handle rotatable thereover and provided with a U-shaped 15 rocking member having one of its arms biased to engage one of said sets of stops.

8. The combination with a plate having a plurality of concentrically related sets of 20 stops severally having sloping and perpendicular faces, of a handle rotatable over said

plate and having a rocking member biased to a position between two of the perpendicular faces of one set of stops, and a pin positioned in said handle and dependent upon 25 pressure to overcome the biasing effect upon said rocking member and permit rotative movement of the handle.

9. The combination with a plate having a plurality of concentrically related sets of 30 stops severally having sloping and perpendicular faces, of a handle rotatable over said plate and having a rocking member biased to engage one set of stops, and means located in the handle and dependent upon pressure 35 for engaging the perpendicular face of the one or the other of two stops of the other set when moved in opposite directions.

In testimony whereof, I have hereunto subscribed my name this 19th day of Feb., 1919.

PAUL L. MARDIS.
